(57) CLAIM

The ornamental design for a wine aerator, as shown and described.

DESCRIPTION

FIG. 1 is a front right perspective view of wine aerator; FIG. 2 is an enlarged front view thereof;

FIG. 3 is rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawing are included for the purpose of illustration and form no part of the claimed design.
